CLAIM

The ornamental design for a napkin disposal unit, substantially as shown and described.

DESCRIPTION

FIG. 1 is a front, raised perspective view of a napkin disposal unit according to the invention; FIG. 2 is a front view of the napkin disposal unit of FIG. 1; FIG. 3 is a rear view of the napkin disposal unit of FIG. 1; FIG. 4 is a right side view of the napkin disposal unit of FIG. 1; FIG. 5 is a left side view of the napkin disposal unit of FIG. 1; FIG. 6 is a top view of the napkin disposal unit of FIG. 1; and, FIG. 7 is a bottom view of the napkin disposal unit of FIG. 1.

The dash-dash broken lines in the figures show portions of the napkin disposal unit which are not part of the claimed design. The dash-dot broken lines represent boundaries and form no part of the claimed design.
